ATTORNEY.

UNITED STATES PATENT OFFICE

ARTHUR C. KOOTZ, OF MILWAUKEE, WISCONSIN

MOP

Application filed August 15, 1927, Serial No. 212,934. Renewed August 29, 1931.

The invention relates to mops and more particularly to polishing or dusting mops of the type wherein the mop material is removably secured to the mop head or frame so that it may be readily taken off for washing or renewal.

The objects of the invention are to provide a mop-supporting frame which extends through a channel or pocket in the mop body and the ends of which are separable for receiving the mop but are readily secured together by a snap connection which positively prevents the removal or the working off of the mop from the frame and which may be manipulated without the use of any tools.

A further object of the invention is to provide a mop frame for receiving the mop material, one of whose ends is secured to the handle connector and the other end having a readily separable snap connection therewith.

The invention further consists in the several features hereinafter set forth and more particularly defined by claims at the conclusion hereof.

In the drawing Fig. 1 is a perspective view of a mop embodying the invention with the handle shown detached;

Fig. 2 is a rear end view of the mop, parts being broken away;

Fig. 3 is a detail sectional view of the mop frame taken on the line 3—3 of Fig. 2;

Fig. 4 is a detail plan view of the rear end portion of the mop, showing the frame in an open position;

Fig. 5 is a detail sectional view similar to Fig. 3, showing certain modifications;

Fig. 6 is a detail side elevation view of a modified form of snap connection;

Fig. 7 is a detail sectional view taken on the line 7—7 of Fig. 6.

In the drawing the numeral 6 designates the mop body, 7 the supporting frame, 8 the handle and 10 the handle connector.

The mop body 6 is of known construction,

consisting of strands 11 of yarn or other suitable mop material stitched together and to inner and outer fabric strips 12 and 13 which are folded to form a frame-receiving pocket or channel 14.

The mop frame 7 in each instance is formed from a strip of metal, preferably wire of substantially loop-shaped form which is preferably of triangular shape with its ends 15 and 16 extending inwardly from its periphery 55 from the rear end thereof.

The handle connection 10 is of sheet metal or other suitable material formed to provide a handle-receiving socket portion 17, the ears 18 of which are drawn toward each other to clamp the handle in the socket by a bolt 19 and to provide spaced or forked end portions 20 apertured to receive a pivot-bolt 21 provided with a clamping nut 22.

In the construction shown in Figs. 1 to 3, 65 inclusive, a clip 23 formed of sheet metal or other suitable material is bent around and over the eyed or hooked end 24 of the end portion 15 and its upper portion 25 projects beyond the end 24 and forms a keeper 70

for the end 26 of the end portion 16 of the frame, this upper portion 25 preferably being grooved at its rear edge, as shown at 27, so that by moving the end 26 from its separated position shown in Fig. 4 to the 75

dotted line position there shown it may be readily snapped down into locked position so as to positively secure the ends of the frame together, the resiliency of the frame permitting of this action and the connection acting 80

generally similar to a safety-pin. The sides of the clip 23 prevent lateral displacement of the separable end of the frame and have alined holes 28 through which the pivot-bolt 19 passes, the forked portions 20 being held against said sides by the tightening up of the nut 22 so as to retain the handle in the desired angular relation and permit it to be moved to any desired angular position relative to the frame.

In the construction shown in Fig. 5 the clip 23 has been eliminated, the end portions 15 being bent over the pivot-bolt 21 to form a hook 29, the free end of the portion 16 being adapted to be inserted between said hooked end and its shank, as shown in said figure, and the forked portions 20 of the handle connector being clamped by the bolt 21 against the sides of the hook 29 and forming side 10 guards preventing lateral displacement of the pin end of the frame.

In the construction shown in Figs. 6 and 7 the pivot-bolt 30 has a shoulder 31 formed thereon and an extension 32 forming an eye 15 into which the separable end 33 of the mop frame may be inserted or snapped, the other end 34 of the frame being formed into an eye similar to the eye 24 and receiving the bolt 30 which is threaded to take a wing-nut 35. The 20 arms 20 of the handle connection 10 straddle the eyed end 34 and a washer 36 may be disposed adjacent the nut 35. With this construction the free or separable end of the frame may be sprung into the eyed extension 25 32 to secure the ends of the frame together.

I desire it to be understood that this invention is not to be limited to any particular form or arrangement of parts except insofar as such limitations are specified in the claims 30 or necessitated by the prior art.

What I claim as my invention is:

1. In a mop, the combination of a mop-receiving frame having separable ends extending inwardly of its periphery, one of 35 said ends being of hooked formation, a handle connector, a pivot for said handle connector extending through said connector and the hooked end of said frame, the other end of 40 said frame being in the form of a pin, and means forming a slidably releasable locking connection for the pin end of said frame.

2. In a mop, the combination of a mop-receiving frame having separable ends extending inwardly of its periphery, one of said 45 ends being of hooked formation, an apertured clip secured to said hooked end, a handle connector, a pivot for said handle connector passing through said connector, clip and the hooked end of said frame, the other end of 50 said frame being in the form of a pin releasably engageable in said clip.

3. In a mop, the combination of a resilient 55 mop-receiving frame having separable ends, a handle connector, and a pivot member provided with an opening at one end and on which said handle connector is pivotally mounted, one of said ends being secured to said pivot member, the other of said ends 60 slidably fitting in the opening of said pivot member and adapted to be releasably held therein, and means for securing the handle connector, pivot member and frame in assembled relation.

4. In a mop, the combination of a resilient 65 mop-receiving frame having separable ends,

a handle connector, a pivot pin provided with an eyed end and a threaded shank and on which said handle connector is pivotally mounted, one of said ends being mounted on said shank, the other of said ends slidably fitting in the eyed end of said pivot member and adapted to be releasably held therein, and a clamping nut mounted on said threaded shank.

In testimony whereof, I affix my signature. 75
ARTHUR C. KOOTZ.
